UNITED STATES PATENT OFFICE.

CHARLES F. COLEMAN, OF PHILADELPHIA, PENNSYLVANIA.

DESICCATING APPARATUS.

1,286,538.

Specification of Letters Patent.

Patented Dec. 3, 1918.

Application filed March 6, 1917. Serial No. 152,823.

To all whom it may concern:

Be it known that I, CHARLES F. COLEMAN, a citizen of the United States, residing at 2910 N. Stillman street, Philadelphia, in the county of Philadelphia and State of Pennsylvania, have invented new and useful Improvements in Desiccating Apparatus, of which the following is a specification.

10 This invention relates to an improved evaporating apparatus and has particular reference to the type employed in extracting residual salts from sodic or other semi-liquid solutions.

15 An object of the invention is to provide an improved apparatus of the above character wherein is embodied means for treating viscid fluids to the action of steam heated surfaces, in order that the hydric 20 components of the fluid will pass off in a volatile state, leaving a residuum of coagulated or concentrated matter, which is dried, collected and disintegrated by suitable mechanism for commercial purposes.

25 A further object is to position the above mechanism in a vacuum chamber, so that the drying process, to which the substance to be treated is subjected, will be expeditiously and efficiently carried out, by reason 30 of a lowered boiling point temperature.

Further objects will be in part obvious and in part pointed out hereinafter.

For a further comprehension of the invention, reference is to be had to the accompanying drawings, forming a part of this specification, in which like characters of reference indicate the same parts, and wherein—

Figure 1 is a vertical longitudinal sectional view taken through the evaporating apparatus, constructed in accordance with the principles of the present invention.

Fig. 2 is a vertical transverse sectional view taken on the line 2—2 of Fig. 1.

Fig. 3 is a horizontal sectional view, the plane of which being indicated by the line 3—3 of Fig. 2.

Fig. 4 is a horizontal sectional view disclosing the complemental drying mechanism.

Fig. 5 is a detail view taken along the line 5—5 of Fig. 4.

Figs. 6 and 7 are fragmentary detail views.

55 Referring more particularly to the drawing, my improved evaporating and desiccating apparatus consists of a housing 1, the latter being formed from any suitable material, and of any desired proportion, which of course will be determined by the capacity or 60 output required of the apparatus. The housing usually embodies removable front and rear walls 2 and 3, stationary side walls 4, and a top and bottom 5 and 6 respectively, said members defining an internal drying 65 chamber B. The front and rear walls are removable, in order that the chamber will be readily accessible. One method for securing the walls 2 and 3 in position is to equip the same with bifurcated projections 7, into 70 which are adapted to be positioned a plurality of pivoted bolts 8, carried by a permanent part of the housing, hand wheels or nuts 9 being threaded upon the extremities of the bolts, so as to frictionally retain 75 the walls 2 and 3 in operative and secured relation with the associated parts of the housing and to conveniently permit of their removal therefrom. In the preferred embodiment of the invention, a pipe 10, or its 80 equivalent, communicates with the interior of the housing, said pipe leading from a suitable form of a suction pump (not shown) which when in operation will serve to exhaust whatever air is in the housing, 85 whereby a vacuum or a partial vacuum will be created therein. By producing a vacuum chamber within the housing a distinct advantage is derived, by reason of the fact that the boiling temperature of the substance acted upon by the apparatus will be considerably lower than when subjected to ordinary atmospheric pressure, thus hastening the general evaporating process. However, it might be advisable to state at this 90 juncture that the use of the vacuum chamber is only necessary during the desiccation of certain substances, as other materials may be acted upon under ordinary conditions with efficient results, and it will therefore 100 be seen that the invention is not limited in its scope solely to use in connection with a vacuum chamber.

Rotatably mounted within the chamber B is an endless belt 15, which is trained over, 105 usually, vertically spaced drums 16 and 17. The belt is preferably formed from a thin sheet of pounded metal, usually copper, so as to possess extreme flexibility and durability, the meeting extremities of the belt 110 being suitably fused or treated, so as to eliminate the presence of a joint or crevice

in the outer surface thereof. As above stated the belt is preferably made from metal, as the latter material is not likely to be affected by the chemical action of materials deposited thereon, and, as it will be evident, it will permit of the convenient removal of caked or dried materials, and can be conveniently cleaned so as to be maintained in a sanitary condition.

- 10 The lower drum 16, as shown in Fig. 2, is preferably hollow in order to receive a suitable heating fluid, therefore, one end of the drum is rotatably supported by a hollow shaft 18, journaled in a packing gland 19, formed in one of the permanent side walls of the housing, while the opposite end of the drum is provided with a stub shaft 20, rotatably mounted in a fixed bearing 21, carried by one of the walls 4. Steam, obtained 15 from any convenient source, is admitted to the interior of the drum 16 by way of the shaft 18, so that the periphery of the drum will be heated by the effects of the steam, which will in turn impart heat to the rotatable belt. A worm gear 22 is secured upon the shaft 18 exteriorly of the housing, and meshes with a similar gear 23, fixed to the drive shaft 24, and it will be apparent 20 that when the latter is revolving, similar movement will be transmitted to the drum and its coöperating belt. The condensation of steam which will collect in the drum 16 may be discharged therefrom in any convenient manner, however, one method by 25 which this can be accomplished is to insert a stationary outlet pipe 25 of relatively small diameter into the shaft 18, and it will be apparent that the pressure imparted by the steam upon the collected water will be 30 sufficient to force the latter out of the drum by way of the outlet pipe 25, as the end of the outlet pipe is downturned and extends into proximity to the wall of the drum.
- 35 The upper drum is preferably mounted in adjustable bearings, in order that the height of the drum within the housing may be varied to regulate the tension of the belt 15. This adjustable feature includes a fixed shaft 27 extending between the side walls of 40 the housing, and about which are fulcrumed arms 28, disposed on opposite ends of the drum 17. Bearings 29 are mounted on the arms and in which is journaled a shaft 30 utilized to support for rotation the drum 17.
- 45 In order to regulate the positions of the arms 28, bolt members 31 have their lower extremities pivotally connected with the outer ends of the arms 28, the upper extremities of said bolts passing through openings 50 formed in the top 5, and are threaded to receive adjusting nuts 32. By regulating the positions of the nuts upon the ends of the bolts 31, the oscillating movement of the drum 17 may be readily controlled.
- 55 Interposed between the drums 16 and 17

and bearing upon the inner surface of the belt 15, are a plurality of spaced steam-heated casings 35, preferably formed from thin sheet metal and of substantially the same width as the belt. Steam or any other suitable heating fluid is admitted into the casings 35 by way of an entrance pipe 36, extending to one of the permanent walls of the housing, said pipe is branched, so as to enter each of the casings 35 at their upper ends. 70 Steam entering the casings 35 will circulate through the same until condensation occurs and collects upon the bottom of the casing. This collection of water is removable from the casings by way of an outlet pipe 38. 80 It will be evident that the casings 35 will bear upon the belt 15 upon major surfaces of the latter, and in conjunction with the drum 16 will heat said belt sufficiently to evaporate the liquid matter adhering to its surfaces. 85

As one of the several methods for depositing liquid or a semi-liquid substance upon the belt 15, I preferably employ a liquid-receiving trough 40, which is adapted to surround the approximate lower half of the 90 drum 16. The substance to be desiccated is transmitted to the tank 42 by way of a supply pipe 41, extending into the chamber B by way of the side wall 4. The liquid is maintained at a predetermined level in the trough 95 by providing the latter with an overflow lip 41' which is positioned above the liquid-receiving tank 42. A pipe 43 leads from the tank to a circulating pump, which forces the liquid of the tank to the trough 40. Thus 100 when the belt 15 is traveling in the direction of the arrow indicated in Fig. 1, it will collect upon its outer surface a certain quantity of the material contained by the trough 40, and will convey the latter toward the heating casings 35, in order that the liquid matter contained thereby will be subjected to a process of evaporation, and to thereby enable its residuum to be collected. 105 A leveling blade 45 is adapted to bear upon the outer surface of the belt 15 at a point immediately above the trough 40, so that the amount of the substance collected by the belt may be regulated before the latter is exposed to the heat of the casings. The relation existing between the blade 45 and the belt 15 may be controlled by suitable screw mechanism 46. It will be evident that the substance carried by the belt will be subjected to the heat of the casings during the major portion of its travel, whereby practically all of the liquid matter contained therein will be 110 evaporated by the heat of the belt. 115

When the substance is in this semi-moist condition, it is collected from the belt by 120 means of a knife 47, which bears upon the belt at a position substantially contiguous to the drum 16. The substance scraped off of the belt is discharged into a chute 48, and is discharged for further drying into a 125 130

supplemental dryer 49, the latter mechanism being located within a housing 51 having an internal chamber C in communication with the chamber B of the housing 1, as clearly shown in Fig. 1.

Positioned within the chamber C and supported by the walls of the housing 51, are a plurality of steam-heated shelves 52, which are preferably hollow and are filled with steam to suitably heat the surfaces thereof. A vertically journaled shaft 53 is mounted within the housing 51, and is provided with a beveled gear 54, which meshes with a similar gear 55 carried by a driven shaft 56, for effecting the rotation of the shaft 53. Fixed upon the shaft 53, and rotatable over the shelves 52 are a plurality of disintegrating arms 57 and 58. The arms are provided with obliquely extending vanes 59 and 60, carried by the arms 57 and 58 respectively. When the material is discharged upon the upper shelf 52 by the chute 48, the same is collected by the revolving arm 57 and is pushed over the heated surface of said shelf, and is gradually moved toward the center of the latter by the obliquity of the vanes 59, so that the substance will be discharged upon the lower shelf 52 by way of an opening 61 formed in the upper shelf 52. When the material is deposited upon the lower shelf 52 it is again subjected to the revolving action of one of the arms 58, but in this instance the material is gradually moved outwardly toward the rim of the shelf 52 by the staggered positions of the vanes 60 upon the arm 58. The movement of the substance upon the shelves 52 will be relatively slow so that the same will receive the full benefit of the heat arising from said shelves so that the substance will be thoroughly dried, and in some instances, pulverized. The action of the arm 57 and its associated vanes 60, as stated before, carries the substance upon the lower shelf 52 toward the edge of the latter, whence it is discharged into a duct 62 communicating with the upper surface of the lower shelf 52. The duct discharges the dried and thoroughly desiccated substance into a conveyer 63, so that the substance may be discharged from the apparatus for collection. The conveyer is rotated by any suitable means, but in this instance a motor 64 is employed, having a beveled gear 65 fixed to its crank shaft 66. The gear 65 is adapted to mesh with gears 67 and 68 carried upon a sleeve 69, said sleeve being slidably keyed to the outer end of the conveyer shaft 70. A manually operated lever is yoked upon the sleeve 69, and is employed to throw one or the other of the gears 67 and 68 into mesh with the motor gear 65, in order to control the direction of rotation of the conveyer. Thus when the conveyer is rotating in a certain direction, the material discharged thereupon by the

duct 62 will be conveyed toward a substance-receiving receptacle 72, which is removably positioned within a casing 73 depending from the conveyer frame. When the receptacle 72 has been filled to its capacity, a sliding door 74 is positioned above the open end of the same so as to prevent the further entrance of material therein, then the lever 71 is operated to cause the conveyer to revolve in a reverse direction, which will carry the substance deposited thereon to a similar receiving receptacle disposed on the opposite end of the conveyer frame. By providing the conveyer reversing means and the sliding door 74, the apparatus may be continuously operated without disturbing the condition of the vacuum within the chambers B and C, as will be clearly understood.

In conclusion, attention is directed to the forced system of liquid circulation for transmitting fluid to the belt 15. It will be noted fluid is conducted to the tank 42 by means of the supply pipe 41, leading from any suitable source of fluid supply. The vacuum within the chamber B serves to siphon the fluid from its base of supply into the tank, and a manually operated valve 80 governs the flow of fluid through the pipe 41. The fluid flows from the tank 42 through a pipe 43 to a suitable form of pump 81, the latter operating to return the fluid by way of the pipe 82 to the trough 40.

This construction is exceedingly important as it prevents the precipitation of the fluid within said trough, provides means for forcibly conducting fluid to said trough, and finally permits the fluid to more readily adhere to the belt 15. The latter feature is due to the fact that if the fluid contained by the trough did not circulate, steam bubbles would be created between the portions of the belt engaging with the drum 16, and the fluid within said trough, this would have the effect of preventing the fluid from properly contacting with the belt. However, by reason of the pump 81, the fluid is continuously circulated, so that the accumulation of the aforesaid steam bubbles will be prevented, thus insuring the unrestricted engagement of the fluid with the belt 15.

From the foregoing it is thought that the advantages and features of the present invention will be readily understood by those versed in the art, and therefore, a more extended explanation with regard to its minor details will be accordingly omitted.

Having described the invention, what is claimed as new and patentable is:

1. A device of the character described comprising a housing, vertically spaced drums revoluble within said housing, an endless belt trained about said drums, a liquid receptacle below the lower drum whereby said belt may dip therein during its travel, a pair of spaced vertically extending casings 125

disposed between said drums, inlet and outlet pipes communicating with said casing, the outer sides of said casings being convex and bearing outwardly against the inner sides of said belt, and means for tightening said belt whereby it will be held in frictional engagement with said casing.

2. A device of the character described comprising a housing, vertically spaced drums revolvable within said housing, an endless belt trained about said drums, a liquid receptacle below the lower drum

whereby said belt may dip therein during its travel, a pair of spaced vertically extending casings disposed between said drums, and inlet and outlet pipes communicating with said casings, the outer sides of said casings being convex and bearing outwardly against the inner sides of said belt and the upper drum being bodily adjustable for tightening said belt into frictional engagement with said casings.

In testimony whereof I affix my signature.
CHARLES F. COLEMAN.
